(57) **CLAIM**

The ornamental design for a grill grate, as shown and described.

DESCRIPTION

FIG. 1 is a perspective view of a first embodiment of the ornamental design of a grill grate including a base, cooking surface and a top cover;

FIG. 2 is a perspective and exploded view of the various components included within in the embodiment of the grill grate illustrated in FIG. 1, however the top cover is not illustrated in this drawing;

FIG. 3 is a top plan view of the grill grate illustrated in FIG. 1;

FIG. 4 is a cross-sectional side elevation view taken at line 4-4 of FIG. 3 of the grill grate illustrated in FIG. 1;

FIG. 5 is an enlarged perspective view of the cross-sectional view of FIG. 4 of the grill grate illustrated in FIG. 1.

FIG. 6 is a top plan view of the grill grate illustrated in FIG. 1;

FIG. 7 is a cross-sectional side elevation view taken at line 7-7 of FIG. 6 of the grill grate illustrated in FIG. 1;

FIG. 8 is an enlarged perspective view of the cross-sectional view of FIG. 7 of the grill grate illustrated in FIG. 1;

FIG. 9A is a perspective view of a second embodiment of a top cover that can be placed on the embodiment illustrated in FIG. 1;

FIG. 9B is a side elevation view of the second embodiment of a top cover illustrated in FIG. 9A; and,

FIG. 9C is a top plan view of the second embodiment of a top cover illustrated in FIG. 9A.

The elements shown with broken lines form no part of the invention although the applicant reserves the right to amend the drawings or submit continuation applications with drawings in which some of the broken lines may be presented as solid lines and thus become part of the claim.
